tion of Great Britain

Application September 9, 1946, Serial No. 695,623
In Great Britain September 17, 1945

5 Claims. (Cl. 204—219)

1

This invention relates to improvements in electrolytic cells, and more particularly to cells having a liquid electrode such as mercury.

Various electrolytic cells are known having as one electrode a sheet of mercury flowing on the smooth bottom of a trough-shaped vessel slightly inclined to the horizontal, the second electrode being formed of plates or blocks of solid material, usually graphite or another form of carbon, arranged a short distance above the surface of the liquid electrode, and having their undersurfaces substantially parallel thereto. Such liquid electrode cells may be used, for example, for the electrolysis of brine. In copending application of Carter and Glass Serial No. 695,622, filed September 9, 1946, there is described such a cell having the solid electrode plates or blocks attached to the lid, and having means by which the height of the electrodes relative to the liquid electrode can be adjusted very readily and accurately without interrupting the electrolysis, which comprises screw adjusting means for raising and lowering the lid adapted to be operated from outside the cell, and sealing means at the join of the lid with the fixed part of the cell allowing relative movement of the one part with respect to the other. In one form of the invention the lid of the cell was provided with a skirt, and the lower trough-shaped part of the cell was provided with a channel adapted to receive the skirt, in which channel was a resilient deformable rubber packing contacting both the skirt and the wall of the channel. In use the rubber packing was covered by the mercury cathode which thus formed a seal.

We have now found that a very convenient electrolytic cell having a flowing liquid electrode allowing accurate adjustment of the inter-electrode distance without dismantling is one comprising a flat base portion without upwardly extending side walls, a cover portion carrying a solid electrode and forming a cap over the base portion on which the liquid electrode flows, and a liquid tight seal between the cover and the base capable of being repeatedly made and broken, and means for adjusting the height of the cover portion relative to the base portion.

According to the present invention therefore an electrolytic cell of the liquid electrode type comprises a flat-topped base, without upwardly extending walls, on which the liquid electrode flows, a solid electrode supported above the base, a cover having a skirt enclosing said base and said solid electrode, a liquid-tight seal adapted to be made and broken between the skirt and

2

the periphery of the base, and means for adjusting the height of the cover relative to the base. Advantageously the liquid tight seal is formed by a deformable resilient packing contacting the skirt and the periphery of the base below the level of the liquid electrode. Advantageously also the resilient packing is disposed in a groove extending around the peripheral faces of the base. Preferably the packing is formed of an endless inflatable rubber tube capable of being filled with fluid under pressure to create the seal and of being evacuated to break the seal.

In one form of the invention the cell comprises a long flat steel base plate supported by girder members or otherwise so that its length is slightly inclined to the horizontal. Around the bottom edges of the plate metal keeper strips are bolted, and the adjacent outer edges of the plate and of the metal strips are bevelled so as to form a groove extending right around the sides, or peripheral faces, of the base plate. An endless rubber tube having a projecting fin is disposed in the groove with the fin clamped between the base plate and the keeper strips, and the tube is joined to a connection by which the interior of the tube can be either evacuated or filled with water under pressure. The cover portion of the cell comprises a flat steel plate with a skirt, that is, a downwardly projecting vertical portion extending around the edges, which extends downwards below the level of the base plate. The cover portion thus forms a cap which is a loose fit over the base when the rubber tube is deflated, but which fits sufficiently closely for the gap between the two to be sealed when the rubber tube is filled with water under pressure through the tube bearing on the inner surface of the skirt and on the bevelled faces of the base plate and metal strip. The cover is lined with non-conducting material resistant to chlorine such as ebonite, and is supported by a number of pillars at the sides of the cell bearing on lugs projecting laterally. The height of the cover can be adjusted by screw adjusting means either located at the lugs, or forming part of each pillar. The anode of the cell is formed of a number of carbon or graphite blocks within the cover and attached thereto by carbon rods which pass through it in a gastight manner and which also provide the means for supplying current to the anodes. The cell is also provided with means for flowing mercury over the base portion, for flowing brine through the space between the mercury and the anode, and for withdrawing gases generated by the electrolysis.

With such an apparatus the spacing between the anode blocks and the mercury surface, or, what is the equivalent, between the anode blocks and the base plate, can be adjusted within very fine limits by deflating the rubber tube when the cell is emptied and operating the screw adjusting means forming part of the support for the cover. After the adjustment the rubber tube can again be filled with water under pressure, thus making the seal again, and the cell is ready for re-use. The adjustment can thus be made without dismantling the whole cell or separately moving each of the rods supporting the anodes. The anodes can fill the whole of the space above the electrolyte, as described and claimed in the patent of Hirsh and Carter No. 2,503,337 dated April 11, 1950, suitable provision being made for withdrawing gaseous chlorine at intervals along the path of the electrolyte, and the cell can then be used for the electrolysis of brine using a high brine speed as described in copending application of Hirsh and Carter Serial No. 695,804, filed Sept. 9, 1946. This has not been possible in the types of cell used hitherto, since there has been a gap between the anode and the lid; increasing the speed of the brine would have caused electrolyte to flow over the anodes instead of between them and the cathode.

In using a cell of the type described above for electrolysis of a sodium chloride brine, the lid portion and the base portion are assembled with the latter sloping slightly so as to allow the mercury to flow over it, the inter-electrode gap is adjusted by means of the screw adjusting means, and the rubber tube is filled with water under pressure to form the seal. The cell is then put into operation and is worked until voltage measurements indicate that the inter-electrode gap has become too great for satisfactory use. During the whole of this time mercury will fill the space above the rubber tube seal and between the edge of the base plate and the skirt, thus protecting the rubber from the action of the brine and of the chlorine so that it will retain its pliability and resilience. When the inter-electrode gap has become too great for satisfactory use, the electrolysis is stopped, the cell emptied of brine and mercury, and the seal between the skirt of the lid and the base plate is broken by evacuating the rubber tube. The necessary alterations to the screw adjusting means are then made to reduce the gap to its proper value, and the seal is remade by again filling the rubber tube with water. The electrolysis can then be recommenced. By making use of the flexibility of the rubber tube, particularly if a relatively wide gap is left between the two portions of the cell and if a relatively thick tube is used, it is even possible to make slight adjustments to the inter-electrode gap without breaking the seal, and thus without interrupting the electrolysis.

Various modifications of the invention are possible. Thus the carbon rods supporting the solid electrodes may take the form of tubes which can be used as the gas offtakes for removing the electrolysis gas from the interelectrode space. Also, instead of fitting the screw adjusting means to the lid portion, the latter may be fixed and the base portion made moveable by screw adjusting means. It is also possible to support the lid by a plurality of hydraulic rams disposed at intervals around its perimeter, the vertical adjustment of the lid then being achieved by supplying or removing water from the rams. This method of adjusting the height of the lid is capable of pro-

viding a particularly smooth and gradual movement of the lid as a whole.

Again, the base portion of the cell may consist of a flat topped block or table of concrete, with a groove of semicircular or triangular section to hold the resilient packing. Again, instead of providing the groove in the base portion it may be provided in the inner surface of the skirt of the lid, the base portion being then provided with a skirt to allow the seal to be made even with the base portion in its highest position. However, it is preferable for the groove to be in the base portion, since movement of the one part with respect to the other does not then increase the quantity of mercury retained in the cell at any time, nor is the head of mercury above the seal increased when the base portion is relatively close to the top of the cell.

It is also possible to omit the groove altogether, the deformable packing being then fastened to a skirt around the base portion, or to the skirt of the cap, for example by means of a fin projecting from the deformable packing.

The upper parts of the carbon rods carrying the solid electrodes may be provided with a cover, for example of copper or brass, as described and claimed in copending application of Ravenscroft, Serial No. 695,624, filed Sept. 9, 1946, to prevent exudation or seepage of electrolyte through pores in the carbon.

In any of the variations of the invention in which a rubber sealing tube is used cold water may be circulated through it continually so as to keep it cool as well as form the seal; the life of the tube can then be extended considerably, even though the cell is operated at a considerably elevated temperature.

The invention is further illustrated by the accompanying diagrammatic drawings, not to scale, in which like numbers represent like parts.

Figure 1 is a vertical section of one form of the electrolytic cells of this invention, in which the base portion is a flat-topped table of concrete, and the sealing means consists of an endless band of sponge rubber.

Figure 2 is a vertical section of another form of our cells in which the base portion is a flat steel plate and the sealing means consists of an endless inflatable rubber tube.

Figure 3 is a vertical section of another specific embodiment of our cells.

Figure 4 is a section of the inflatable tube used as sealing means in the cells shown in Figures 2 and 3.

Figure 5 shows the method of attaching the inflatable tube to the base portion in Figures 2 and 3.

Figure 6 is a partial, sectional view showing a side elevation of the cells shown in Figures 2 and 3, and illustrating the manner in which the tube and valve for inflating the inflatable tube are arranged with respect to the remainder of the apparatus.

Figure 7 is a partial view showing a side elevational section of a modified form of the cells of this invention, in which the deformable, resilient packing between the skirt and the plate-like base of the cell is carried in a groove in the skirt.

In the drawings, 1 is a flat base portion carrying a flowing mercury cathode 2. Above the mercury cathode flows aqueous electrolyte 3. The cells are provided with appropriate means (not shown) for supplying mercury and fresh electrolyte to the cell, for removing amalgam and spent electrolyte, for removing gases evolved in

the electrolysis, and for supplying electric current to the electrodes.

Each cell has a cover 4 of steel lined with ebonite or other insulating material resistant to the products of electrolysis, carrying a number of solid carbon anode blocks 5 (one of which is shown) each depending from carbon rods 6 (as in Figures 1 and 2), or from carbon tubes 6a (as in Figure 3), which pass through openings in the cover 4 and through which current is supplied to the anode by means shown only in Figure 2. In the drawings the joint between the cover 4 and the anode supports 6 or 6a is sealed by a sealing composition 7 or by a rubber ring 7a, but any other suitable method of making the joint gas-tight may be employed. The cover 4 is provided with a downwardly projecting skirt 8, also lined with ebonite or other suitable material, which extends downwards below the level of the mercury cathode 2. From each side of the cover project a number of horizontal lugs 9 (one on each side being visible in Figures 1 to 3). Each lug is supported by a pillar-bolt 11 having a stand 10, collar 12 and locknut 13, which controls the height of the cover 4 relative to the base 1.

Referring now more particularly to Figure 1, the concrete base portion 1 is provided with a peripheral groove 14 of semicircular cross-section in which is positioned an endless band 15 of sponge rubber having an impermeable outer skin. The band 15 in the unstretched state is slightly less in total length than the peripheral groove 14 and it is therefore held in the groove by the elasticity of the sponge rubber. The clearance between the inner, ebonite lined face of the skirt 8 and the side of the concrete base 1 is such that a mercury-tight seal is made between them by the band 15. A space running the full length of the cell between the anode 5 and cover 4 is freely accessible to the anode gases which are led out of the cell by one or more gas outlet tubes 16. In putting such a cell into operation the cover 4 carrying the anodes 5 is adjusted by means of the pillar bolts 11 so that the under surface of the anodes is at the desired distance above the flat top of the base 1. The mercury circulation and then the electrolyte circulation are started, and the current is switched on. As electrolysis proceeds the under surface of the anode 5 wears away. In order to maintain the gap between the anode 5 and the mercury layer 2 at its initial value the cover is lowered at intervals by the required amount of rotation of the pillar bolts 11. The resilience of the band 15 ensures that the seal will be maintained during the process of adjustment.

Referring now to Figure 2, the anodes 5 are fitted closely against the lining of the cover 4, leaving no longitudinal channel in the cell, accessible to electrolyte or anode gases, above the level of the interelectrode space. Thus the electrolyte 3 is forced to flow along the cell through the interelectrode space. The mercury electrode 2 flows on a flat steel plate 1 supported on girders 17 and provided with a peripheral rubber tube 15a capable of being filled with water under pressure to the make the seal between the base plate 1 and the skirt 8 and of being evacuated to break the seal. The rubber tube is shown in section in Figure 4 and the arrangements for attaching it to the under side of the base plate are shown in Figure 5. It will be seen that the tube 15a is triangular in section and is provided with a fin 19 attached to one angle. The tube is in the form of a continuous ring which requires to be

stretched by a small amount to enable it to sit in the groove formed by the bevelled edges of the base plate 1 and the keeper strip 20 (Figure 5). The fin 19 is gripped between the base plate 5 and the keeper strips which are held in position by countersunk bolts 21 passing through holes punched in the fin. A thin rubber ring 22 makes a mercury-tight seal between the head of the bolt and the base plate. The tube 15a has a valve (not shown) which passes through a seating in the keeper strip and carries a connection whereby water pressure or suction may be applied to the tube.

Each anode block 5 in Figure 2 is supported by two carbon rods 6, which pass through holes in the cover 4. The part of the carbon rods which projects out of the cell is covered by a brass cap, screwed on to the rod 6 and pressing a hard washer against the rubber ring 7a. The brass caps carry the electrical connections for the anode, and are fitted with a grease nipple so that grease or oil under pressure may be forced against the upper surface of the rods 6 to prevent seepage of electrolyte through the rods. Narrow vertical spaces extending across the cell between adjacent anode blocks to permit escape of anode gas from the interelectrode space communicate with independent gas offtakes 16, which are fitted with vertical extension tubes (not shown), of a height at least equivalent to the head of brine in the cell below the gas offtake, to convey the anode gass to a common header.

Referring now to Figure 3, the sealing means and base plate are the same as for the cell of Figure 2, and as shown in more detail in Figures 4 and 5. Between the anodes 5 and the cell cover 4 there is provided a layer 23 of material resistant to the anode gases, preferably of a resilient nature such as sponge rubber coated with neoprene, to fill any gap between 4 and 5 which would otherwise be liable to permit longitudinal flow of electrolyte through the cell above the interelectrode space. The anode blocks 5 are supported in the cover by hollow carbon tubes 6a, two for each block, which pass through the cover 4 and the layer of resilient material 23 into the block 5, and terminate at the top 18 of a vertical slot cut in the block 5 and extending across the whole width of the anode to allow escape of gas from the interelectrode space. The tubes 6a are provided with electrical connections (not shown) and with vertical extension tubes (not shown) leading the anode gas from the separate anode blocks to a common header. The cells shown in Figures 2 and 3 are adapted for high speed flow of electrolyte and permit the electrolyte to be introduced into the cells at superatmospheric pressure. They are therefore eminently suitable for the electrolysis of brine by the process described and claimed in copending application of Hirsh and Carter, Serial No. 695,804, filed September 9, 1946. The height above the base plate to which the passages leading off chlorine, e. g., tubes 16 in Figure 2 and tubes 6a in Figure 3, must extend will be determined by the head of brine at the cell inlet. This head will, in turn, depend on the size of the interelectrode gap and the linear velocity of the brine. With satisfactory operation under high speed brine conditions, the head of brine corresponds to about $\frac{1}{2}$ inch per foot length of cell. It is convenient to carry all the passages to the same height, although it will be appreciated that the height of the passages at the end by which the brine leaves will not need to be as great as at the other end.

Figure 6 illustrates the means for inflating the inflatable tube 15a. Thus, at one point along the bottom periphery of the inflatable tube 15 there is molded as an integral part of the tube a T-piece 24 and this T-piece passes through a hole 25 provided therefor in the keeper strip 20. The free end of the T-piece 24 is attached to a metal tube 26 provided with a valve 27. The opposite end of this metal tube 26 connects to a source of fluid pressure (not shown), such as a water line. By opening the valve 27, water under pressure can be introduced into the inflatable tube 15a after which the valve 27 is closed and the inflated tube retained under pressure so as to keep the cell sealed.

In the modification shown in Figure 7, the resilient packing material 15 is carried in an indentation or groove 28 in the skirt 8.

We claim:

1. An electrolytic cell of the liquid electrode type comprising a base having a flat top on which the liquid electrode flows and dependent peripheral vertical sides, a cover having a dependent vertical skirt enclosing said base, a solid electrode enclosed within the cover carried by the cover above said base, a liquid-tight seal adapted to be made and broken, comprising a deformable, resilient packing in the form of an inflated, endless rubber tube positioned between the dependent skirt and the peripheral vertical sides of the base, and means for adjusting the height of said cover relative to the base.

2. A cell as claimed in claim 1, wherein said

inflated, endless rubber tube is positioned in a groove extending around the peripheral vertical sides of the base.

3. A cell as claimed in claim 1, wherein said inflated, endless rubber tube is positioned in a groove on the inner face of said dependent skirt.

4. An electrolytic cell according to claim 1, in which said solid electrode is of such size relative to said cover that no space exists between the top and sides of said electrodes and the inside portions of said cover.

5. An electrolytic cell according to claim 1, in which all of the vertical and horizontal space between said solid electrode and said cover is filled with a resilient composition, whereby longitudinal flow of electrolyte through the cell is restricted entirely to the interelectrode space.
